INVENTOR.
May Thompson.
BY Hazard & Miller

ATTORNEY.

UNITED STATES PATENT OFFICE.

MAY THOMPSON, OF LOS ANGELES, CALIFORNIA.

HAIR-DRIER AND SUNSHADE.

1,283,358.

Specification of Letters Patent. Patented Oct. 29, 1918.

Application filed July 1, 1918. Serial No. 242,781.

To all whom it may concern:

Be it known that I, MAY THOMPSON, a citizen of the United States, residing at Los Angeles, in the county of Los Angeles and 5 State of California, have invented new and useful Improvements in Hair-Driers and Sunshades, of which the following is a specification.

My invention relates to hair driers and 10 sunshades and consists in the novel features herein shown, described and claimed.

The present invention is an alternative construction or modification of the construction shown in my companion application for 15 hair driers, filed March 28, 1918, Serial Number 225,832.

Figure 1 is a perspective showing a hair drier embodying the principles of my invention in use.

20 Fig. 2 is a plan of the frame lying flat as it is cut from the material.

Fig. 3 is a perspective of the finished hair drier.

Fig. 4 is an enlarged fragmentary plan of 25 the connecting means shown in Fig. 3, parts being broken away and shown in section to illustrate the details of construction.

Fig. 5 is a view analogous to Fig. 3 and showing a modified form of connecting 30 means.

Fig. 6 is an enlarged fragmentary sectional detail on the line 6—6 of Fig. 5.

Fig. 7 is a plan view of modified form of my invention.

35 The frame 1 is cut from a sheet of good glazed cardboard or other stiff material and has a circular outer edge 2 and a circular central opening 3 eccentric to the outer edge 2; there being a slot 4 of considerable width 40 extending from the opening 3 to the outer edge 2 and forming radial edges 5 and 6. Lacing eyelets 7 and 8 are formed near the edge 5 and mating eyelets 9 and 10 are formed near the edge 6. The frame thus 45 constructed is dipped in warm paraffin wax or other suitable waterproof material to form an inner coating 11 and an outer coating 12 of waterproof material. A lace 13 is threaded through the eyelets 7, 8, 9 and 10 50 to draw the edges 5 and 6 toward each other to the desired extent and then the lace is tied thereby forming a dished hair drier out of the flat frame.

The hair drier and sunshade thus constructed is placed in position, as shown in Fig. 1, with the hair extending upwardly

through the opening 3 and the crown of the head extending into the opening with the widest portion 14 extending forwardly from the upper part of the forehead over the eyes, 60 so that the hair drier protects the face and neck from the sun and exposes the hair to the sun and air. The glazed surface of the cardboard or other stiff material treated with paraffin wax or the like makes a smooth 65 finish which is easily cleaned and which is waterproof.

In the modification shown in Figs. 5 and 6 elastic tapes 15 and 16 are placed across the slot 4 with the edges 5 and 6 near together, and the ends of the tapes are secured to the frame by staples 17, 18, 19 and 20. This form of connection makes the frame yielding to the extent that the tapes 15 and 16 will stretch. 75

A modified construction shown in Fig. 7 is made of a circular piece of cardboard or other stiff material 1' provided with an opening 3' eccentrically disposed therein. The cardboard or stiff material 1' may be 80 waterproofed in the same manner as the other modifications of the invention. The hair drier and sunshade is placed upon the head with the wide portion of the frame in front similar to the hair drier and sunshade 85 illustrated in Fig. 1. The modification shown in Fig. 7 is made of one flat piece of material but the same may be shaped as those shown in Figs. 4 and 5. 90

Various changes may be made in the details of construction without departing from the spirit of my invention as claimed.

I claim:

1. A hair drier and sunshade comprising a frame cut from a sheet of cardboard and 95 having a circular outer edge and a circular central opening eccentric to the outer edge; there being a slot of considerable width extending from the circular opening to the outer edge on radial line; a coating of paraffin wax applied to the frame, and means for drawing the edges formed by the slot together to dish the frame. 100

2. A hair drier and sunshade comprising a frame cut from a sheet of cardboard and 105 having a circular outer edge and a central opening eccentric to the outer edge and a slot cut from the central opening to the outer edge on radial lines, and means for drawing the edges formed by the slot together. 110

3. A hair drier and sunshade comprising a frame cut from a sheet of stiff material and

having a circular outer edge and a central opening eccentric to the outer edge and a slot cut from the central opening to the outer edge on radial lines and having eyelets along the edges formed by the slot, and a lace in the eyelets for drawing the edges together.

4. A hair drier and sunshade comprising

a frame cut from a sheet of stiff material having a rounded outer edge and an opening eccentrically disposed therein and a coating of paraffin applied to the frame. 10

In testimony whereof I have signed my name to this specification.

MAY THOMPSON.
